UNITED STATES PATENT OFFICE.

LOUIS HOFFMAN, OF DULUTH, MINNESOTA, ASSIGNOR, BY MESNE ASSIGNMENTS, TO STEAM PRESSING IRON COMPANY, A CORPORATION OF DELAWARE.

TAILOR'S GOOSE OR SADIRON.

Application filed May 9, 1919. Serial No. 295,867.

To all whom it may concern:

Be it known that I, LOUIS HOFFMAN, a citizen of the United States, residing at Duluth, in the county of St. Louis and State of Minnesota, have invented certain new and useful Improvements in Tailors' Gooses or Sadirons, of which the following is a specification.

My invention relates to a tailor's goose or sad iron, and more especially to an implement of the type adapted to apply moisture to the goods or garment during the operation of pressing the same.

One of the objects of the invention is to provide novel means for controlling the application of moisture to the goods of garment during the pressing operation for which the implement is used. The invention has for further objects to improve and simplify the construction of flat-irons or sad irons of the self heated, moistening type.

The invention is illustrated, in a preferred embodiment, in the accompanying drawings, wherein—

25 Fig. 1 is a plan view of the device.

Fig. 2 is a longitudinal sectional view on line 2—2 of Fig. 1.

Figs. 3 and 4 are plan sections taken on lines 3—3 and 4—4, respectively, of Fig. 2.

30 Fig. 5 is a vertical section on line 5—5 of Fig. 1.

Figs. 6 and 7 are vertical sections on lines 6—6 and 7—7, respectively, of Fig. 2.

35 Fig. 8 is a fragmentary sectional plan on line 8—8 of Fig. 2.

Like characters of reference designate like parts in the several figures of the drawings.

The body of the iron is, as stated, preferably made of aluminum (the use of this metal not being claimed herein as it is claimed in my copending application Serial No. 343,409, filed Dec. 8, 1919), and in the particular construction shown is composed of three parts or sections, a base section 25, an intermediate section 26 and a top section 27. These three sections are fastened together by a screw bolt 28 at the forward end of the iron and two bolts 29 at the rear end of the implement (Fig. 6). The intermediate section is a shell providing a chamber 30 for a heating element, the latter consisting preferably of a gas burner composed of two pipes 31 having burner perforations 32 on their under surfaces (Fig. 8), the pipes being fixed in a web 33 at the back

of the base member 25. The web is formed with a gas port 34 (Figs. 2, 6 and 8) supplied with gas by a pipe 35 screwed into the web, pipe 35 being provided with a shut-off cock 36 and with a nipple for a flexible tube (not shown). The intermediate member 26 and base member 25 are provided at their meeting edges with openings 38 to admit air to the burner chamber, the web 33 just referred to being preferably formed with an opening 39 for the same purpose. The products of combustion escape through openings 40 at the top of the intermediate section (Figs. 2 and 7).

The handle 41 of the iron is preferably made of wood and is fastened by a bolt 42 to upright 43, 44 on a plate 45 secured to the top member 27 of the body by screws 46, a layer 47 of heat insulating material being preferably interposed between the plate 45 and the upper body member 27. The plate 45 and its uprights 43 and 44 are preferably made of aluminum. The top member 27 is formed on the right hand side of the iron with an overhanging projection 48 which acts to deflect the hot gases issuing from the openings 40 on this side of the iron, thereby protecting the hand of the operator. The other side of the iron does not require this protective feature.

The upper section 27 of the body is cored out to form a duct 49 (Fig. 3) and above the opposite extremities of the duct is disposed a valve chamber 50, preferably cast integral with the upper section 27, and formed with a port 51 leading to one end of said duct 49. The base member 25 is cored out to provide a distributing space 53 (Figs. 2 and 4), the portions of the casting above and below this space being united preferably by webs 54 which serve to transmit heat from the upper portion of the casting to the lower portion. Minute perforations 55, shown as considerably exaggerated in the drawings, extend from space 53 through the ironing face of the iron. A pipe 56 connects one end of duct 49 in the upper section 27 with the distributing space 53 in the base member 25. A pipe 57 having a nipple 58 for a hose connection leads to the valve casing 50. The valve chamber 50 is provided with a valve 78 for closing the port 51, the lower end of the valve being provided with screw threads engaging a nipple 79 providing a suitable packing gland. The packing 80 is held in

the gland by a nut 81. An operating lever 82 has a threaded engagement with the upper end of the valve in order that the lever may be adjusted to any desired position 5 with relation to the handle 41 of the iron. By screwing the lock nut 83 down against the operating lever 82 the lever may be locked in the desired adjusted position. The valve 78 is moved to close the port 51 by an 10 outward movement of the lever with relation to the handle 41. Under certain conditions it is desirable that the valve 78 stand open a trifle for some time, in which event the lever 82 may be moved toward the handle 41 to the desired position. The frictional engagement between the valve and the packing gland will be sufficient to hold the valve in any desired position.

I claim:

20 1. A device of the class described, comprising a body having a perforated ironing face and having a passageway leading to the perforations, a handle on said body, a valve for controlling the flow of moistening fluid 25 through said passageway, and a lever for operating said valve, said lever being mounted adjustably with respect to the valve for adjustment towards and from said handle independently of any operation of 30 the valve.

2. In a device of the class described, the combination of a three-part body compris-

ing a base section casting cored out for providing a distributing space, and having a plurality of perforations in its lower face 35 leading from said distributing space, a top section casting cored out for providing an elongated duct leading substantially twice the length of the section at opposite sides thereof, and an intermediate section in the 40 form of a shell adapted with said first-named two sections to provide a heating chamber, a heating element in said heating chamber below said duct, means providing a communicating passageway between said distributing space and one end portion of said duct; means for conducting moistening fluid to the opposite end portion of said duct, and a valve for controlling the inflow of moistening fluid to said duct. 45

3. A sad iron comprising a body having a distributing chamber therein with openings from the chamber to the face of the iron, a handle on said body, a valve having threaded engagement with a fixed element of the 55 iron and adapted upon rotary movement to be moved into and out of operative position for shutting off the flow of fluid to said distributing chamber, and a lever mounted on said valve adapted by a swinging movement 60 toward and from said handle at one side thereof to give said valve an operative rotary movement.

LOUIS HOFFMAN.
